UNITED STATES PATENT OFFICE

GEORGE F. WILFLEY, OF DENVER, COLORADO, ASSIGNOR TO A. R. WILFLEY AND SONS,
INC., A CORPORATION OF COLORADO

CENTRIFUGAL PUMP

Application filed September 10, 1928. Serial No. 304,869.

This invention relates to improvements in centrifugal pumps. Centrifugal pumps are extensively used for handling acid, water containing sand or grit or other liquids. These pumps comprise a casing forming a chamber within which is located a rotatable runner, which is secured to a shaft and which, when rotated at the proper speed, produces the necessary centrifugal force for moving the liquid. In pumps of this type it is not possible to have the opening through which the shaft enters the runner chamber very tight, for the reason that the grit and sand in the water produces an excessive wear, and, when acids are handled the materials must be acid proof and such materials as a rule have a high coefficient of friction and are not adapted to be employed where two movable surfaces come into contact. It is therefore evident that some means has to be provided that will prevent the liquid from flowing out during such times as the pump is inoperative and which will also return slippage liquid into the stream leaving the pump.

In pumps of this type there is always a slippage of the liquid being handled between the impeller and the side of the pump casing. And when this slippage is permitted to flow into the opening through which the rotatable shaft passes, the shaft and the packing will be subjected to excessive wear, which will soon permit an excessive amount of liquid to flow through the stuffing box.

Many attempts have been made to overcome this defect but with little success. Means have been provided for the purpose of adding water to the stuffing box but this must, of course, be free from grit and the stuffing box must be properly tightened to allow only the proper amount of water to enter the pump so as to keep the liquid from flowing outwardly, and in many cases the addition of water to the liquid being pumped is prohibited, as, for example when the pump is used for pumping acids. Port holes have been added to the runner close to the hub to apply what suction there may be in the pump so as to act on the stuffing box, but this causes air to leak inwardly through the stuffing box, and this in

turn interferes with the proper operation of the pump. Auxiliary blades have been added to the side of the runner adjacent the stuffing box, but where this is done there is always a certain amount of slippage between the blades and the side of the casing and this liquid is free to flow outwardly through the shaft opening and produces the excessive wear above referred to.

This invention consists in employing for the impeller an imperforate member which is provided on one side with a set of pumping blades and on the other side with one or more sets of auxiliary blades. The auxiliary blades are on the side of the casing through which the shaft projects and their function is to prevent as much as possible liquid from flowing inwardly toward the shaft between the impeller and the side having the stuffing box. The impeller is provided with a circular groove or depression into which a cylindrical portion of the casing projects and this portion has a groove about its outer circumference which is adapted to catch the slippage liquid and return it to the auxiliary blades.

Having thus very briefly described the invention the same will now be described in detail, and reference will be had to the accompanying drawing in which the preferred embodiment thereof has been illustrated and in which:

Fig. 1 is a vertical section through the improved pump.

Fig. 2 is a section on line 2-2, Fig. 1, and

Fig. 3 is a section through an open type runner which is provided with two sets of auxiliary blades and which can be employed in place of the runner or impeller shown in Fig. 1.

Reference numeral 1 indicates the base of the pump and reference numeral 2 designates one of the standards or brackets in which the shaft 3 is rotatably mounted. The upper end of standard 2 is provided with a semi-cylindrical depression 4 and has secured to its upper end a complementary curved member 5, which is held in place by means of bolts 6 in the manner shown in Fig. 2. The circular opening thus formed is provided

95

90

100

with a groove 7 which is adapted to receive the outwardly extending flange 8 of ring 9. This ring is provided on its inner surface with threads 10, which engage corresponding threads in the outer surface of ring 11. Located within ring 11 is a ball-bearing formed by two circular members 12 and 13, which are separated by balls 14 in the usual manner. Ring 12 is of such size that it will just fit 10 the interior of ring 11 and is clamped to the latter by means of two clamping rings 15 and 16, which are held in place by means of bolts.

Ring 13 is attached to the shaft 3 and is 15 held against shoulder 17 by means of a circular nut 18 that has a threaded engagement with the shaft in the manner shown in Fig. 1. Secured to the base 1 and the bracket 2 by any suitable means is a bracket 19. This 20 bracket is provided with a central opening 20 and has secured to it an impeller casing 21. This casing is separated from bracket 19 by means of a plate 22, which is provided with a central hub 23 that extends into the opening 20. A cylindrical member 24 extends 25 through the opening 20 and through the opening in plate 22 into the impeller chamber. The inner end of this cylindrical member is provided with a cylindrical projection 25, whose outer surface has a groove 26. Packing material 27 separates the outer surface of cylindrical member 24 from the wall of the opening 20 and this packing is held in place by means of a clamping ring 28, which 30 is secured to the bracket 19 by means of bolts 29. It is obvious that by tightening the bolts 29, the packing can be subjected to whatever compression may be desired, so as to form a tight joint. As the cylindrical member 24 35 does not rotate, there will be no wear of the packing or of the outer surface of this member, and therefore a tight joint can readily be maintained between the cylindrical member and the hub 23 so as to prevent liquid 40 from flowing outwardly at this point. Shaft 3 extends into the impeller chamber and terminates in a conical portion 30 on which is mounted a runner or impeller 31. This impeller is held in place by means of a nut 32 45 and is provided with a hub 33 which extends through the opening in the cylindrical member 24. The outer surface of hub 33 is machined so as to form a smooth surface and the opening in member 24 has an inwardly 50 extending annular shoulder 34, which serves as an abutment for the packing material 35. A clamping ring 36 is secured to the cylindrical member 24 by means of bolts 37 and serves to hold the packing material under 55 compression, so as to form a stuffing box of the usual construction. The impeller is provided on the side adjacent the inlet opening with a plurality of main pumping blades 38 and on its rear side with a plurality of auxiliary blades 39. These blades are separated

by an imperforate central portion 40. The side of the impeller adjacent the stuffing box is provided with a central circular depression 41, which is adapted to receive the cylindrical projection 25. The impeller is provided on its front side with a surface 42, which is adapted to co-operate with a similar surface 43 on the inside of the impeller chamber. The rear side of the impeller is provided with a surface 44 which co-operates 70 with the surface 45 on the inner end of the cylindrical member 24. Surfaces 42, 43, 44 and 45 are carefully machined and when the parts are properly adjusted form movable joints which permit very little liquid to pass. It is of course apparent that the relatively 75 rotatable surfaces cannot be in actual contact and therefore there is bound to be some slippage between these surfaces. The slippage that flows between surfaces 44 and 45 moves inwardly toward the outer surface of hub 33 and has a tendency to pass outwardly through the stuffing box; this slippage, however, is caught in the groove 26, which directs it back into the auxiliary blades 39, that 80 return it to the discharge stream of the pump. For the purpose of adjusting the distance between the surfaces 42, 43 and 44, 45, the following mechanism has been provided. The construction of the bearing has already been 85 described and from this it will be apparent that when ring 9 is rotated, ring 11 will be moved either inwardly or outwardly, depending on the direction of rotation, and, since the bearing in which shaft 3 is rotated is secured 90 to ring 11 the shaft with its impeller can, of course, be moved in either direction by rotating this ring and in this manner the desired clearance between surfaces 42 and 43 is obtained. Cylindrical member 24 is provided 95 with an end portion 46 which extends into the opening in which ring 11 is located and has its inner surface threaded so as to engage with the outer surface of ring 11. After the clearance between surfaces 42 and 100 43 has been adjusted, the clearance between surfaces 44 and 45 can be adjusted by rotating the cylindrical member 24. After the adjustments have been made the parts may be 105 clamped in adjusted position by tightening 110 the bolts 6.

It will be seen from the above description that in the pump illustrated, the opening through which the shaft 3 enters the impeller casing is sealed by means of packing 115 35 which forms a stuffing box through which the hub 33 extends. This stuffing box tends to prevent liquid from flowing outwardly when the pump is inoperative and also prevents air from being sucked into the pump during operation. The inner end of cylindrical member 24 is provided with a groove 120 26 which serves as means for catching the slippage and returning it to the auxiliary blades by means of which it will be returned 125

to the discharge stream. The action of the groove 26 and the auxiliary blades prevents liquid from flowing outwardly through the stuffing box when the machine is in operation and in this way the stuffing box is kept free from sand or grit and therefore does not wear very fast. By using a stuffing box in the manner described and shown, centrifugal means of the type shown in U. S. Letters Patent, 1,556,657 for closing this opening when the pump is inoperative can be dispensed with and the construction can therefore be greatly simplified. The use of the cylindrical member 24, the stuffing box surrounding the hub 33 and the groove 26 in combination with the auxiliary blades forms a combination of elements that produces the desired result in a new way and it is to this combination that the present application is directed. It is, of course, obvious that it is not necessary that the cylindrical member 24 shall be movable with respect to the impeller housing, as the action of the groove 26 and the stuffing box will remain the same even if member 24 is an integral part of plate 22.

When an open type runner or impeller of the type shown in section in Fig. 3 is employed there must be two sets of auxiliary blades, one set of which is formed by open blades 38^b and the other by openings 39. The main or pumping blades 38^a and the auxiliary blades 38^b must be of the same length so as to maintain a balance and prevent unequal pressures that produce end thrust. The auxiliary blades 39 may be longer than the open blades so as to be capable of producing a greater pressure which will enable the impeller to return the slippage liquid. The slippage between the auxiliary blades 38^b and the adjacent inner surface of the casing wall 22^a passes into the groove 26 which directs it into the auxiliary blades 39 by means of which it is returned to the outgoing stream of liquid.

From the above description it will be apparent that by means of the expedient of providing a stuffing box and the means for returning slippage to the auxiliary blades, a simpler construction is obtained without the sacrifice of any advantage.

Having described the invention what is claimed as new is:

1. A centrifugal pump, comprising, in combination, a casing forming a runner chamber provided at one side with an inlet opening, the other side having an enlarged central opening, a cylindrical member extending through the central opening, means for forming a seal between the wall of the central opening and the outer surface of the cylindrical member, a shaft extending through the cylindrical member and terminating within the casing, a runner carried by the shaft, said runner having one or more sets of auxiliary blades on the side adja-

cent the cylindrical member, the side of the runner having the auxiliary blades being provided with a circular depression concentric with the shaft, the cylindrical member having a portion extending into the circular depression, said inwardly extending portion having a groove adapted to catch slippage and return it to the auxiliary blades and a stuffing box for forming a seal between the shaft and the cylindrical member. 70

2. A centrifugal pump, comprising, in combination, a casing forming a runner chamber provided at one side with an inlet opening, the other side having an enlarged central opening, a cylindrical member extending through the central opening, means for forming a seal between the wall of the central opening and the outer surface of the cylindrical member, a shaft extending through the cylindrical member and terminating within the casing, a runner carried by the shaft, said runner having one or more sets of auxiliary blades on the side adjacent the cylindrical member, the side of the runner having the auxiliary blades being provided with a circular depression concentric with the shaft, the cylindrical member having a portion extending into the circular depression, said inwardly extending portion having a groove adapted to catch slippage and return it to the auxiliary blades and means for adjusting the position of the cylindrical member in the direction of the axis of the shaft. 85

3. A centrifugal pump, comprising, in combination, a casing forming a runner chamber provided at one side with an inlet opening, the other side having an enlarged central opening, a cylindrical member extending through the central opening, means for forming a seal between the wall of the central opening and the outer surface of the cylindrical member, a shaft extending through the cylindrical member and terminating within the casing, a runner carried by the shaft, said runner having one or more sets of auxiliary blades on the side adjacent the cylindrical member, the side of the runner having the auxiliary blades being provided with a circular depression concentric with the shaft, the cylindrical member having a portion extending into the circular depression, said inwardly extending portion having a groove adapted to catch slippage and return it to the auxiliary blades, a stuffing box for forming a seal between the shaft and the cylindrical member, and means for adjusting the position of the cylindrical member in the direction of the axis of the shaft. 100

4. A centrifugal pump comprising, in combination, a casing forming a runner chamber provided at one side with an inlet opening, the other side having an enlarged central opening, a cylindrical member extending through the central opening and movable 115

with respect to the casing, a shaft extending through the cylindrical member and terminating within the casing, a runner within the casing and connected with the shaft, means for simultaneously moving the runner and the cylindrical member with respect to the casing, while the runner remains stationary relative to the cylindrical member and means for moving the cylindrical member relative to the casing while the runner and shaft remain stationary relative to the casing.

5. A centrifugal pump comprising, in combination, a casing forming a runner chamber provided at one side with an inlet opening, the other side having an enlarged central opening, a cylindrical member extending through the central opening and movable with respect to the casing, a shaft extending through the cylindrical member and terminating within the casing, a runner within the casing and connected with the shaft, means for simultaneously moving the runner and the cylindrical member with respect to the casing while the runner remains stationary relative to the cylindrical member and means for moving the cylindrical member relative to the casing while the runner and shaft remain stationary relative to the casing, said last named means comprising a bracket rigidly connected 20 with the casing, said bracket having an opening, a ring located within the opening and rotatable therein, said ring and bracket having interengaging means that holds the ring from moving in the direction of its axis while 25 permitting it to rotate, a bearing threadedly connected with the ring whereby when the ring and the bearing are rotated relative to each other the bearing will move in the direction of its axis, the outer end of the cylindrical member having a threaded connection with the outer surface of the bearing whereby when the cylindrical member is rotated 30 relative to the bearing while the latter remains stationary with respect to the ring the cylindrical member will be adjusted with respect to the runner and the casing.

In testimony whereof I affix my signature.
GEORGE F. WILFLEY.
